UNITED STATES PATENT OFFICE

OTTO FRITZ KIEHN, OF NEW YORK, N. Y.

TEXTILE WINDING MACHINE

Application filed August 6, 1929. Serial No. 383,930.

This invention relates to textile winding machines of the type which are employed by retailers for rewinding, measuring and examining piece goods.

5 Winding machines of this character have hitherto been constructed in such a manner that the reels or cores were supported on opposite sides or at opposite ends of the machine, thereby requiring considerable time and labor in positioning the bolt of cloth to be wound and in training or threading the same through the machine. In order to overcome this disadvantage, the present invention comprehends a machine which is constructed and

10 designed in such a manner as to dispose both of the reels or cores at the same side of the machine for effecting an economy in time and labor when placing the cloth thereon. A further advantage flowing from this type of 15 machine resides in the fact that the same may be positioned close to the wall of a room without interfering with its use and operation.

The invention furthermore comprehends a 20 textile winding machine of the character set forth which is adaptable for use in connection with the winding of cloth upon reels or upon tubular or other shaped cores employed in the trade.

25 As a still further object, the invention resides in the provision of a slideable arm for the reel holding means which is adjustable to compensate for reels of varying lengths.

The invention further embodies an equalizer means when the fabric is wound from and onto the ordinary type of rectangular reels.

30 Other objects of the invention reside in the comparative simplicity of construction and mode of operation of the winding machine, the economy with which the same may be produced and installed, and the general efficiency derived therefrom.

35 With the above recited and other objects in view, reference is had to the following description and accompanying drawings, in which there is exhibited one example or embodiment of the invention, while the claims define the actual scope of the same.

40 In the drawings:

50 Figure 1 is a side view of the machine.

Figure 2 is a front view thereof.

Figure 3 is a vertical sectional view therethrough.

Figure 4 is a fragmentary detail view partially in section, of the supporting means.

Figure 5 is an end view of the reel supporting means.

Figure 6 is a fragmentary sectional view taken approximately on the line 6-6 of Figure 4.

Figure 7 is a view similar to Figure 4 illustrating the manner in which cloth supporting slats or bars are associated with the device.

Figure 8 is a detail side view of a tubular core supporting element.

Figure 9 is a fragmentary horizontal sectional view through the equalizer device.

Referring to the drawings by characters of reference, the machine includes a frame 70

having transversely spaced end members 10 and 11 which are connected by the upper and intermediate cross rods 12 and 13 and the lower cross rods 14 and 15. The upper portion 16 of each of the end members 10 and 11 is substantially bow shaped or arcuate with their concave portions disposed forwardly. A pair of vertically spaced core or

reel engaging elements 17 and 18 is journaled in the end member 11 and the latter element 80

18 is designed to be driven through any suitable mechanism. A pair of similar core or

reel engaging elements 19 and 20 are suitably supported adjacent the opposite end member

85 and are journaled for rotation with the elements 17 and 18. The elements 17 and 19 are adapted to engage with the opposite ends

of the core or reel of the bolt or cloth to be unwound and the elements 18 and 20 are de-

signed to engage with the opposite ends of the core or reel, upon which core the cloth is

90 to be rewound. The core engaging elements

17, 18, 19 and 20 are of substantially identical construction and are provided with means for clamping cores or reels of varying widths and thicknesses. Each element includes a body 21 which carries a pair of opposed jaws 22 for clampingly embracing the opposite edges of a reel or core, the jaws

95 having confronting substantially U-shaped 100

channels or grooves 23 and said jaws being further bifurcated to straddle the body 21, whereby the furcations 24 which lie on opposite sides of the body are slotted as at 25 to receive therethrough the bolts 26. This permits of the proper setting of the jaws to correspond with the width of the reels or cores which are being used. The elements further include a pair of relatively movable gripping jaws 27 which are designed to engage with and grip the opposite faces of the reels or cores. The gripping jaws 27 are provided with threaded apertures 28, the threads of the aperture of one jaw being oppositely pitched to the threads of the aperture of the other jaw for engagement with the oppositely pitched threaded portions 29 of an adjusting screw which is journaled in the central web 30 of the body 21, it being understood that the adjusting screw is provided with a central annular groove 31 within which the retaining screw 32 engages.

The opposite extremities of the adjusting screw are provided with manipulating handles 33, by virtue of which the adjustment of the jaws may be readily accomplished. The core engaging head 18 is provided with a hub 35 which is keyed to a driving shaft 36 operatively connected with the driving mechanism, while the remaining elements 17, 19 and 20 are each provided with a hub 37 within which an anti-friction bearing 38 is arranged to receive a trunnion 39. The trunnion 39 of the element 17 is secured to the end frame member 11, while the trunnions 39 of the elements 19 and 20 form the terminals of stub shafts 40. The stub shafts 40 of the elements 19 and 20 are axially slidably in spaced ears 41 and 42 at the opposite ends 40 of an arm 43. Each stub shaft 40 has secured thereto a collar 4, against which one terminal of a coiled expansion spring 44 engages with its opposite terminal abutting the ear 42 to normally effect movement of the stub shaft inwardly until the collar 4 abuts the ear 41. This causes the elements 19 and 20 to be normally moved a limited distance toward the corresponding elements 17 and 18 and at the same time tensions the elements 19 and 20 against movement in an opposite direction. The arm 43 is provided with a central hub 45 which receives the intermediate cross rod 14, whereby to mount the arm 43 for sliding movement on said cross rod and transversely of the machine, whereby the elements 17 and 19 and 18 and 20 may be approximately adjusted to the length of the cores or reels which are being used. The arm 43 is maintained against turning movement while permitted to slide through the medium of a spline 46 and spline groove 47. In practice, the arm 43 is moved on the cross rod 14 to a position where the elements 19 and 20 will be spaced from the elements 17 and 18 a distance slightly less than the lengths

of the cores or reels being used, whereby the cores or reels may be associated with the elements 17 and 19 and 18 and 20 by compressing the springs 44 so that the tension of the springs serves to maintain the cores or reels in position between the clamping and gripping jaws 22 and 27. In order to maintain the arm 43 in its shifted position, a set screw 49 extends through the hub 45 and is adapted to be manipulated for frictionally engaging the cross rod 14. It will be observed that the arm 43 is substantially V-shaped with the free extremities projecting forwardly and disposed in superposed relation so that the bolt reel to be unwound and the core upon which the cloth is to be rewound are disposed in close proximity to each other and in vertically spaced relation at the forward side of the machine, to facilitate the application of the bolts to the core or reel engaging elements and the threading of the cloth through and the removal of the rewound bolt from the machine without the necessity of the operator having to walk from one side of the machine to the other.

A measuring roll 50 is journaled in the end members 10 and 11 and is suitably connected with a measuring device 51 supported by the end member 11. The measuring roll is disposed at the upper end of the bowed upper portions 16 of the end members 10 and 11 and a pressure roller 52 cooperates therewith to maintain the cloth in contact with the periphery thereof. A guide blade 54 is supported by the cross rod 15 and is especially designed for engagement between the folds of a folded cloth so that its terminal engages with the bight to cause the cloth to run straight and to maintain the same crease. This guide blade is supported by a bracket 55 having a hub 56 which surrounds the cross rod 15 and is provided with a set screw 57. In practice, the bolt of cloth arranged on its core is supported by the core engaging elements 17 and 19 and the end of the cloth is trained upwardly around the measuring roll 50 and between the same and the pressure roll 52. The end of the cloth is then brought downwardly and engaged around a receiving core upon which the cloth is to be rewound, it being understood that the receiving core is placed in the core engaging elements 18 and 20. The receiving core is rotated by the drive shaft 36 which imparts motion to the element 18.

In view of the fact that the flat cores or reels upon which the cloth is usually wound have a tendency to cause the cloth to jump and jerk, equalizing rollers for compensating for the slack caused by the flat winding are employed, and said equalizing rollers 60 and 61 are mounted respectively at points to engage the cloth where it leaves the bolt to be unwound and where the cloth arrives approximately at the rewinding point. The

equalizing rollers are mounted for rotation on non-rotary cross shafts 62 which are secured in the hubs 63 of reciprocating carriers 64. The carriers 64 in turn are provided with sheaves 65 which roll on guide rods 66 supported in brackets 67 attached respectively to the end members 10 and 11 of the frame. The carriers in turn are moved in one direction by means of springs 68 which also serve to tension the carriers against movement in the opposite direction. Under this construction and arrangement, it is apparent that the shifting of the lays of the cloth due to the flat winding of the same is controlled and equalized to prevent jerking and to insure even unwinding of the cloth from and winding of the cloth on the bolts.

In order to render the machine adaptable for winding of the cloth on thin cardboard sheets, the body 21 is slotted as at 70 to permit of the insertion thereinto of the apertured extremities of slats 71, as illustrated in Figure 7, which are retained by bolts 72 which pass through said extremities and extra holes in the body 21 therefor. The cardboard cores in this instance may be clamped in place by the gripping jaws 27 while the slats 71 offer the desired rigidity until the bolt is formed on the cardboard cores. After the bolt is thus formed, it is obvious that the slats 71 may be removed by disconnecting the ends from the bodies 21.

The elements 17, 18, 19 and 20 may also be employed for supporting tubular cores by attaching a frusto-conical element 75, such as illustrated in Figure 8, to the core supporting elements.

From the foregoing, it will thus be seen that a cloth winding, rewinding, measuring and examining machine has been devised which is adaptable to practically any type and size of core. It will also be observed that the device may without alteration be employed for winding cloth from a loose bolt onto a core. While rewinding the cloth, it is apparent that the operator may examine the same as it passes from the measuring roller to the rewinding core.

What is claimed is:

1. In a machine for rewinding, measuring and examining cloth, a framework including spaced parallel connected end members, vertically spaced core engaging elements journaled on one of said end members, one of which elements is driven and a transversely slidable bearing arm having correspondingly vertically spaced core engaging elements journaled thereon, means for normally urging the latter core engaging elements toward the former and for tensioning the latter core engaging elements against movement in the opposite direction, and locking means for holding the slidable bearing arm in approximate adjustment to the width of the cores being used, the tensioned means serving to

permit of the exact adjustment of the core engaging elements to accommodate the cores being used, the said core engaging elements including two pairs of jaws, said pairs of jaws being respectively adjustable to the width and thickness of the bolt cores being used for embracingly engaging the ends of said cores.

2. In a machine for rewinding, measuring and examining cloth, a framework including spaced parallel connected end members, vertically spaced core engaging elements journaled on one of said end members, one of which elements is driven and a transversely slidable bearing arm having correspondingly vertically spaced core engaging elements journaled thereon whereby to render the machine adjustable to accommodate cores of varying lengths, the said core engaging elements including a pair of jaws for clampingly embracing the side edges of the reel and a separate pair of gripping jaws for engaging the opposite faces of said reel whereby the core engaging elements are adjustable to accommodate reels of different relative width and thicknesses.

3. In a cloth winding machine, a core engaging element including a pair of jaws for clampingly embracing the side edges of a reel or core and a separate pair of gripping jaws for the opposite faces of said reel whereby the core engaging elements are adjustable to coact with reels of relatively different thicknesses and width.

4. In a textile rewinding machine, a main supporting frame including vertically disposed transversely spaced parallel frame members and cross connections therebetween; a pair of superposed fixed rotary driven and idler core supporting elements journaled in one of said frame members and a pair of superposed cooperative adjustable rotary core supporting elements; and a carrier in which said latter core supporting elements are journaled, said carrier being mounted for lateral adjustment on a cross connection between the frame members, said adjustable core supporting elements being journaled in said carrier and normally urged axially toward and tensioned against movement away from the fixed rotary driven and idler core supporting elements and said core supporting elements fashioned to embracingly engage with the opposite ends of the cores and including relatively adjustable core side engaging means and relatively adjustable core side edge engaging means.

5. In a textile rewinding machine, a main supporting frame including vertically disposed transversely spaced parallel frame members and cross connections therebetween; a pair of superposed fixed rotary driven and idler core supporting elements journaled in one of said frame members and a pair of superposed cooperative adjustable rotary core

supporting elements; and a carrier in which said latter core supporting elements are journaled, said carrier being mounted for lateral adjustment on a cross connection between the frame members, said adjustable core supporting elements being journaled in said carrier and normally urged axially toward and tensioned against movement away from the fixed rotary driven and idler core supporting elements and said core supporting elements fashioned to embracingly engage with the opposite ends of the cores and including relatively adjustable core side engaging means and relatively adjustable core side edge engaging means, the former consisting of a pair of clamping jaws and threaded means for advancing the same toward and away from each other to accommodate cores of different thicknesses.

20 6. In a textile rewinding machine, a main supporting frame including vertically disposed transversely spaced parallel frame members and cross connections therebetween; a pair of superposed fixed rotary driven and idler core supporting elements journaled in one of said frame members and a pair of superposed cooperative adjustable rotary core supporting elements; and a carrier in which said latter core supporting elements are journaled, said carrier being mounted for lateral adjustment on a cross connection between the frame members, said adjustable core supporting elements being journaled in said carrier and normally urged axially toward and tensioned against movement away from the fixed rotary driven and idler core supporting elements and said core supporting elements fashioned to embracingly engage with the opposite ends of the cores and including relatively adjustable core side engaging means and relatively adjustable core side edge engaging means, the former consisting of a pair of clamping jaws and threaded means for advancing the same toward and away from each other to accommodate cores of different thicknesses and the latter consisting of a pair of jaws having confronting grooved faces and means mounting the same for adjustment toward and away from each other to accommodate cores of different width.

Signed at New York city, in the county of Bronx and State of New York, this 31st day of July, A. D. 1929.

55 OTTO FRITZ KIEHN.
